(57) **CLAIM**

The ornamental design for a display screen with a graphical user interface, as shown and described.

DESCRIPTION

FIG. 1 is a front image of a display screen with a graphical user interface showing our new design, according to a first embodiment.

FIG. 2 is a front image of a display screen with a graphical user interface showing our new design, according to a second embodiment.

FIG. 3 is a front image of a display screen with a graphical user interface showing our new design, according to a third embodiment; and,

FIG. 4 is a front image of a display screen with a graphical user interface showing our new design, according to a fourth embodiment.

The ornamental design that is claimed is shown in solid lines in the drawings. In the drawings, the dash-dot broken lines are for the purpose of illustrating portions of the graphical user interface and forms no part of the claimed design. The dot-dash broken lines are for the purpose of illustrating the display screen and forms no part of the claimed design.

1 Claim, 4 Drawing Sheets
